INDUCTANCE HAVING A SELF-INDUCTION
INDEPENDENT OF TEMPERATURE

Mendel Osnos, Berlin, Germany, assignor to Tele-funkens Gesellschaft fur Drahtlose Telegraphie m. b. H., Berlin, Germany, a corporation of Germany

Application September 9, 1932, Serial No. 632,418
In Germany September 29, 1931

5 Claims. (Cl. 175—35)

This invention relates to an improved inductance having a particular form of construction which will not be subject to self-inductive fluctuations caused by temperature changes deforming the conductor.

The object of the invention is to eliminate the fluctuations of self-inductance caused by temperature changes by employing a quartz tube which is filled with a plurality of flexible copper conductors and combined with mercury.

For example, one form of my invention is the placing and retaining within a glass or quartz tube a flexible conductor, mercury is poured in the glass tube so that it will fill up the interstices and gaps between the glass and the copper conductor. Since glass or fused quartz is not subjected to any substantial amount of expansion, the length of the conductor between the terminals will not be subjected to any increase in length, whereas the mercury which is located inside the glass tube and almost fills the entire space, will be free and able to expand or contract between the interstices formed by the conductors 2 without any substantial value of the inductance between the terminals being altered. In this manner the current is in part caused to flow through the copper and partly through the mercury so that the length of the ensuing conductor depends only upon the length of the glass tube and not the copper conductor.

Still better, another modification of the above embodiment is the construction wherein the glass or quartz tube is filled (either by blowing or by suction) with copper dust or copper filing chips, and in addition mercury is drawn by suction into the tube in order to fill up the spaces left between the constituent copper particles and the latter and the glass walls.

In lieu of the copper filing chips mentioned above, relatively short copper conductors could be used with advantage which are arranged to fill up almost the whole space inside the tube, whereas the mercury would then serve only as an electrical connection between the constituent copper conductors.

A better understanding of this invention will be had by referring to the drawing in which

Fig. 1 shows an inductance of this invention in a developed form;

Fig. 2 shows substantially a single turn of the inductance coil;

Fig. 3 shows several turns of the improved inductance coil of this invention.

Fig. 1 shows this embodiment in developed form.

1 denotes the glass or quartz tube, 2 massive or

tubular copper conductors, 3 mercury, 4 the end electrodes which dip into mercury. It will be seen that in this manner each individual piece of copper is capable of contraction and expansion without occasioning an incidental change in the over-all length of the inductance.

If the tube is to be bent circularly or annularly so as to provide a coil with a plurality of inductive turns, the copper rods or conductors must naturally be as short as possible in order to render them freely mobile within the tube so that they may not experience any mechanical stress. However, since the spaces and gaps must be filled up with mercury, and therefore as the latter has a far greater electrical resistance than copper, this will result in an increase of aggregate loss resistance. In order that this resistance loss may be minimized, the tube of the modification shown in Fig. 2 may be made of several parts 1', each one thereof containing a freely mobile copper conductor 2, while the spaces between the constituent conductors 2 are substantially filled up with mercury 3.

Various other modifications of coil constructions will suggest themselves to those skilled in the art, such as a spiral coil or a cylindrical shape of coil, which would be employed in a similar manner as mentioned above.

I claim:

1. An inductance having a self-inductance which is independent of temperature, comprising an insulating tube filled with a plurality of metallic conductors and the interstice between said metallic conductors being filled with a liquid conductor.

2. An inductance having a self-inductance which is independent of temperature, comprising a quartz tube filled with a plurality of small copper particles impregnated with mercury.

3. An inductance having a self-inductance which is independent of temperature, comprising a quartz tube filled with relatively short copper conductors inter-connected by mercury.

4. An inductance having a self-inductance which is independent of temperature, comprising an insulator tube filled with a plurality of rectilinear metallic conductors with the spaces between said metallic conductors connected by mercury.

5. An inductance coil having a self-inductance which is independent of temperature, comprising an insulator tube filled with a plurality of metallic conductors, the interstice between said metallic conductors being filled with a liquid conductor.

MENDEL OSNOS. 110
